UNITED STATES PATENT OFFICE.

RICHARD K. HOCHMANN, OF SAN DIEGO, CALIFORNIA.

HIGH-SPEED REVOLVING-HOOK SEWING-MACHINE.

1,096,360.

Specification of Letters Patent Patented May 12, 1914.

Application filed March 20, 1913. Serial No. 755,730.

To all whom it may concern:

Be it known that I, RICHARD K. HOCHMANN, a citizen of the United States, and resident of San Diego, county of San Diego, State of California, have invented certain new and useful Improvements in High-Speed Revolving-Hook Sewing-Machines, of which the following is a specification.

This invention relates to revolving hook sewing machines and has particular reference to high speed machines designed for commercial use as distinguished from the ordinary domestic use.

The novel features of the invention will be apparent from the following description, taken in connection with the accompanying drawings.

In the drawings, Figure 1 is an end elevation partly broken away of the working parts of the machine; Fig. 2 is a bottom plan view; Fig. 3 is a side elevation partly broken away to show the driving means; Fig. 4 is a vertical section on the line 4—4 of Fig. 3; Fig. 5 is a longitudinal section of the revolving hook and bobbin holder; Fig. 6 is a plan view of the bobbin holder; Fig. 7 is a side elevation of the revolving hook; Fig. 8 is a face view of the spring used in the bobbin holder; and Fig. 9 is a cross section on the line 9—9 of Fig. 2.

In these drawings I have shown a work plate 1 of the machine and the vertical hollow standard 2 carrying the horizontal portion, on the end of which is mounted the head 3 of the machine, above the work plate. This head has in it the needle bar 4 and the presser foot bar 5, and it will be understood that the rotary shaft 6 mounted in the horizontal portion of the standard 2 is suitably connected to reciprocate the needle bar, power being applied to the rotary shaft from any suitable source by means of the pulleys 7. On the removable face plate of the head 3 suitable guides and tension mechanism for the thread are placed, and it will be seen by reference to Fig. 1 that the pressure on the presser foot may be regulated by turning the nut 8, thereby changing the tension on the spring 9 tending to force the presser foot downward.

Below the work table there is mounted a rotary shaft 10 driven by any suitable means from the rotary shaft 6, the particular form of driving means shown being a belt 11 having perforations engaging pins

on pulleys carried by the two shafts, and it will be observed that the pulley on the lower shaft 10 is smaller than that on the upper shaft the proportions being such as to give the shaft 10 two revolutions for each revolution of the shaft 6. The shaft 10 carries on its forward end a rotary hook ring 12 which in the form shown is connected to the rotary shaft by the intermediate thin metal section 13, which is of dished shape and is secured to the shaft and to the ring by screws or rivets. The outer edge of the hook ring 12 is cut away at 14 and a projecting sharp point or hook 15 is on one edge of said cut away portion facing it, its purpose being to catch the loop of thread formed by the needle as the revolving hook turns. The revolving hook has an interior circular groove 16 which serves as a bearing for the circumferential rib 17 on the bobbin holder 18.

The bobbin holder as shown in Fig. 6 is made up of a casing open on one side to receive the bobbin 19 and closed on the opposite side, the outer edges of the casing made of thin metal being tapering or inwardly inclined toward the circumferential rib 17, so as to permit a loop of thread to pass easily around it. In order to avoid as much as possible unnecessary weight, part of the material of the casing may be removed, holes 20 being formed for this purpose. On the outer inclined face of the bobbin holder suitable holes and slots may be made through which the thread from the bobbin passes and by which tension may be given to it, such features lettered 21 and 22 being shown in Fig. 6. A hollow standard 23 is carried by the rear wall of the bobbin holder concentrically therewith and projecting out toward the opening in the opposite face of the holder so as to receive the bobbin 19. The bobbin 19 is made much larger than those ordinarily used in rotary hook machines carrying a large amount of thread, thus reducing work of rewinding the bobbins when the machine is in use. A plunger or movable member 24 fits within the hollow shaft 23 and a retaining member 25 is hinged to it at 105 26 extending across the end of the hollow shaft and lying against the outer end flange of the bobbin holding it in place in the casing. This cross member for retaining the bobbin is so shaped as to permit the thread 110 to pass easily over its outer side, one end of the retaining member extending out beyond

the edge of the bobbin and being curved in as shown in Fig. 5. The plunger 24 has at its inner end a head 27 centering and guiding it, and against which a spring 28 bears, this spring fitting at its outer end against the closed end of the hollow shaft 23. There is preferably a slot 29 in the end of the hollow shaft 23 into which the cross member 25 can pass. A spring 30 of any suitable construction is preferably used in the back of the casing around the shaft 23 to press the bobbin out against the retaining member 25 so as to hold it firmly in position preventing rattling, and this spring may be made in the shape of a thin plate as shown in Figs. 5 and 8 having arms bent to bear against the back wall of the casing. It will be observed that the retaining member 25 can be turned on its pivot 26 until the shorter end of it is in line with the shaft 23, and the spring 28 may be allowed to draw it partly within the shaft so that the bobbin can pass over the retaining member and into position around the shaft and then the retaining member can be withdrawn and turned into the position shown in Fig. 5 where it will hold the parts in place. The bobbin holder has a portion 31 removed at one point on its circumference and the bearing rim 17 is also cut away at this point terminating on one side in the sharp hook or point 32 for engaging the loop of thread. In operation this cut away portion of the bobbin holder will be at the top so that the needle may enter it forming the loop in position to be carried against the hook 32 by the hook 15 on the revolving ring. It will be observed that the hook 15 has an inclined surface leading down to the contracted end of the opening 33 and thus when the loop is engaged by this hook the thread will be carried into the point 33 which is across the bearing groove 16 so that the thread is carried by the hook from the forward side to the rear side of the hook 32 and as the ring 12 rotates the thread will necessarily be engaged by the hook 32.

It will be observed that the bobbin holder being loosely mounted within the hook ring would turn with it unless means are provided for preventing its rotation and therefore I have made use of two oscillating arms adapted to alternately enter the openings 34, 35 in the forward or inclined face of the casing so as to prevent it from turning as the hook turns. It will be seen by reference to Fig. 1 that these openings are in the upper portion of the casing and the arms 35 and 36 which enter them are pivoted at the sides of the casing extending upwardly, and having inwardly projecting ends entering the openings. The arms 35 and 36 are pivoted to shafts 37, 38 which have secured to them short arms 39, 40 and a link 41 is pivoted to and connects the ends of those arms whereby the arms 35 and 36 will move to-

gether. A link 42 is connected to the link 41 and is pivoted at 43 to an arm carried by the rock shaft 44. The rock shaft 44 extends along the machine from the front to a point below the hollow standard 2 and at that point has secured on it an arm 45 to which a rod 46 is pivoted, that rod having on its upper end a bearing member 47 fitting a cam 48 carried by the upper rotary shaft 6. The rotation of the shaft 6 thus reciprocates the rod 46 rocking the shaft 44 and to the link connections rocking the arms 35 and 36 on their pivots to make them alternately engage and disengage the bobbin casing, one of those arms always being in engagement. The timing of the operation of these arms is of course so adjusted that each arm will be disengaged at the time that the loop of thread is being carried to and past it by the hook 15. It will be observed that the guide member 49 is secured to the under surface of the face of the machine and projects down around the end of the arm 35 so as to guide the thread as the loop is being pulled up preventing it from being caught by the inwardly projecting end of the arm 35, this guide member being shown in the form of a wire.

The mechanism for feeding the cloth embodies a feed arm 50 which is pivoted at one end and which has the ratchet teeth 51 at the other end adapted to project slightly up through an opening in the work plate of the machine immediately below the presser foot. The feed arm is pivoted to the upper end of an arm 52 carried by the rock shaft 53 and it will therefore be seen that when the shaft 53 is rocked the arm 50 will move back and forth across the machine to give the necessary feed to the cloth. The shaft 53 extends along the machine to a point beneath the standard 2 and at that point has an arm 54 secured to it. A link 55 is pivoted to the arm 54 and to a link 56 at its opposite end. The link 56 is pivoted at one end to the rod 57 which rod is held in place rigidly by a clamping screw 58 but which can be moved to different positions around the arc 59 within the slot 60 above the work plate of the machine. This movement of the rod 57 to different positions changes the angle of the link 55 to the link 56, these two links operating as a toggle and thus the leverage of the toggle can be varied by varying the position of the rod 57. The rod 60 is pivoted at 61 at the point where links 55 and 56 are connected and this rod 60 extends up through the hollow standard 2 having at its upper end a bearing member fitting over a cam carried by the rotary shaft 6 so that as the shaft 6 turns the rod 60 will be reciprocated. The change in the leverage or angle due to the change in the position of the rod 57 will cause this reciprocation of the rod 60, to have a different effect on the shaft 53.

turning it different amounts according to the adjustment. It will be observed that the rod 57 can be adjusted at any time without interfering with the operation of any parts 5 of the machine and that the adjustment can be made even while the machine is in operation to change the feed and consequently the length of the stitch.

The feed bar 50 must not only be reciprocated but must be raised and lowered at the proper time to feed the cloth and the means for causing this rise and fall of the feed bar is shown in Figs. 1 and 4. A rock shaft 62 is mounted below the work plate of the 15 machine adjacent the shaft 53 and it is connected by means of the arm 63 and rod 64 to a cam on the rotating shaft 6 whereby it will be rocked as the shaft 6 turns. At the other end of the machine and beneath the 20 head carrying the needle bar, the shaft 62 has secured thereto an arm 65 which has flexible connection to an arm 66 secured to the feed bar 50, the arms 65 and 66 being substantially parallel and turning simulta- 25 neously on their pivot. The connecting means shown consists of a member 67 having its ends fitting in sockets in the arms 65 and 66 so as to maintain the spaced relation of those arms and a coiled spring 68 which is 30 under tension tending to draw the two arms together. By this arrangement the oscillation of the arm 65 will be imparted to the arm 66 and will thus give the feed arm 50 its up and down motion, and this operation will 35 take place without interfering with the horizontal motion imparted to the arm 50 by the rock shaft 53.

Having thus described the invention, what is claimed is:

1. The combination with a rotary shaft of a revolving hook ring carried thereby, a bobbin holder mounted in said ring, a rock shaft, two arms pivoted at their lower ends on opposite sides of said holder and extending upwardly in front of said hook ring to engage said holder on opposite sides to prevent rotation, link connections from said rock shaft to said arms at points near their pivots whereby a small movement of said 45 link connections will cause a much larger movement of the operative ends of said arms, and means for oscillating said rock shaft periodically.

2. The combination with a rotary shaft of 50 a revolving hook ring carried thereby, a bobbin holder mounted in said ring, a rock shaft,

two arms separately pivoted and adapted to engage said bobbin holder on opposite sides alternately to prevent rotation, link arm connections between said arms near their pivots 60 to said rock shaft, and means for oscillating said shaft periodically.

3. The combination with a rotary shaft of a revolving hook ring carried thereby, a bobbin holder mounted in said ring, a rock 65 shaft, two arms separately pivoted and adapted to engage said bobbin holder on opposite sides alternately to prevent rotation, link arm connections between said arms near their pivots to said rock shaft, and 70 means for giving said rock shaft a quick oscillation once during two revolutions of said hook ring.

4. In a sewing machine, the combination with the table plate, of a rotary shaft above 75 said plate for operating the needle bar, a rotary shaft below said plate carrying a rotary hook ring on its end, a bobbin holder with a coöperating hook within said rotary hook ring, arms adapted to alternately engage 80 said holder on opposite sides to prevent rotation, means operated by said needle bar shaft for turning said rotary hook shaft, and independent means operated by said needle bar shaft for alternately moving said arms 85 into and out of engagement with said bobbin holder to permit the passage of a loop of thread.

5. In a sewing machine, the combination with the table plate, of a rotary shaft above 90 said plate for operating the needle bar, a rotary shaft below said plate carrying a rotary hook ring on its end, a bobbin holder with a coöperating hook within said rotary hook ring, arms adapted to alternately engage 95 said holder on opposite sides to prevent rotation, cloth feeding mechanism below said plate, means operated by said needle bar shaft for turning said rotary hook shaft, independent means operated by said needle bar 100 shaft for alternately moving said arms into and out of engagement with said bobbin holder to permit the passage of a loop of thread, and independent means for operating said cloth feeding mechanism from said 105 needle bar shaft.

In testimony whereof I affix my signature in presence of two witnesses.

RICHARD K. HOHMANN.
